UNITED STATES PATENT OFFICE.

HENRY GIBBS, OF CHICAGO, ILLINOIS, ASSIGNOR TO W. D. ALLEN MANUFACTURING COMPANY, OF CHICAGO, ILLINOIS, A CORPORATION.

GREASE-CUP.

1,248,475.

Specification of Letters Patent.

Patented Dec. 4, 1917.

Application filed June 15, 1916. Serial No. 103,834.

To all whom it may concern:

Be it known that I, HENRY GIBBS, a citizen of the United States, and a resident of Chicago, in the county of Cook and State 5 of Illinois, have invented certain new and useful Improvements in Grease-Cups, of which I do declare the following to be a full, clear, and exact description, reference being had to the accompanying drawing, 10 forming a part of this specification.

My invention relates to that class of grease cups in which provision is made for preventing the accidental rotation or working loose of the cap or cover of the cup, and the invention 15 consists in the features of novelty hereinafter described, illustrated in the accompanying drawing and particularly pointed out in the claim at the end of this specification.

20 Figure 1 is a view in central vertical section through a grease cup embodying my invention. Fig. 2 is an inverted plan view of the cap or cover of the grease cup. Fig. 3 is a plan view of the body portion of the 25 grease cup with the cap or cover removed. Fig. 4 is a perspective view upon an enlarged scale of the cap or cover of the grease cup. Fig. 5 is a detail perspective view of the pin that will depend centrally from the 30 cap or cover. Fig. 6 is a fractional view in section of the cup showing the manner of connecting the pin thereto.

The body A of the grease cup may be formed from stamped metal or as a malleable 35 casting. In the upper part of the body A is formed a shoulder a upon which rests an annular spring B that is opened to form the parallel arms b that project inwardly across the central portion of the body A. 40 The upper part of the body A is exteriorly screw-threaded, as shown, to receive the correspondingly internally threaded cap or cover C that may be made either as a casting or from stamped metal.

45 Centrally of the cap or cover C is formed a polygonal opening c adapted to receive the polygonal upper end d of the pin D. This pin D is formed by being stamped from sheet metal and is of rectangular shape, the width 50 of the lower part of the pin D being greater

than the distance between the parallel arms b of the spring B between which arms the pin D extends when the cap C is in position for use. Below the shank d at the upper end of the pin D is formed a shoulder d' at each 55 side of the pin D, the shoulder d' being adapted to bear against the under side of the top of the cap C.

In assembling the parts, the shank d of the pin D is inserted within the polygonal 60 opening c of the cap C and the upper end of the shank d (which shank is longer than the thickness of the cap) is upset or headed over, as at d² (see Fig. 1), so as to firmly and rigidly hold the pin in position. Inasmuch as the shank d of the pin D is of 65 polygonal shape corresponding to the opening c in the cap C, it is manifest that when the shank of the pin has been inserted within the cap, the pin is securely held against 70 the possibility of rotation with respect to the cap and the shoulder d' of the pin D and the upset or headed portion d² of the shank serve to rigidly secure the pin to the cap. By forming the pin D of stamped 75 metal and with a shank of polygonal shape to set within a polygonal opening in the cap C, an extremely simple and effective means is provided for guarding the pin against rotation, and by providing the pin with one 80 or more shoulders d', the upper end of the pin can be effectively upset, as at d², to rigidly unite the pin to the top of the cap.

Having thus described my invention, what I claim as new and desire to secure by Letters Patent is:—

The combination with the body of a grease cup having a spring, of a cap provided with a polygonal opening therein and a stamped metal pin having a polygonal upper end of 90 uniform thickness with the body of the pin and set within said opening and upset on the top of the cap, said pin having a shoulder below its polygonal end to engage the under side of the cap, said shoulder being 95 of uniform thickness with the body of the pin, the lower portion of said pin engaging said spring.

HENRY GIBBS.
